HUMIDIFIER FOR DETACHABLE CONNECTION WITH CIGARETTE PACKAGES

Robert E. Adair, Highlands, N. J.

Application May 18, 1953; Serial No. 355,445

4 Claims. (Cl. 299—24)

1

This invention relates to a humidifying device adapted for detachable connection with a cigarette package, whereby to maintain and even increase the moisture content of cigarettes enclosed within the package, and thus to prevent undesirable drying out of the cigarettes pending removal thereof from the package for consumption.

Owing to the finely divided or shredded form of tobacco used in paper wrapped cigarettes, the initial moisture content of the tobacco, when the cigarettes are exposed to influence of air after the package is opened, tends to be rapidly dissipated, so that the tobacco not only loses flavor, but the temperature of the fumes, when the tobacco is smoked, rises to an unpleasant degree. Furthermore, in drying out, the shreds of tobacco become brittle and tend to break up or crumble into fine particles likely to be undesirably drawn into the mouth, when the cigarettes are smoked, to the annoyance of the smoker.

Having the above in view, it is an object of this invention to provide a simple humidifier device which can be easily and quickly applied to the opened end of a cigarette package, contiguous to ends of cigarettes contained therein, subject to removal from the package when the latter is empty, so as to be available for reuse in another package.

Another object of this invention is to provide a humidifier device for the stated purposes which is capable of insertion beneath an end wall of the package, after a portion of said end wall is torn away to provide an opening through which cigarettes can be withdrawn from the package interior; the device being so shaped and dimensioned as not to obstruct the latter opening; and the device being provided with a retaining clip means to grip the package end wall, whereby to prevent accidental displacement of the device from its inserted and assembled relation to the package.

The above and other objects will be understood from a reading of the following detailed description of the invention in connection with the accompanying drawings, in which:

Fig. 1 is a top plan view of the humidifier device of this invention.

Fig. 2 is a fragmentary perspective view of an opened cigarette package showing the humidifier device of this invention inserted therein in operative assembled relation thereto.

Fig. 3 is a fragmentary side elevational view of an opened cigarette package, with parts in longitudinal section, showing the humidifier device operatively assembled therewith.

2

Fig. 4 is a bottom plan view of the humidifier device; Fig. 5 is a central longitudinal sectional view thereof; and Fig. 6 is a transverse vertical sectional view of the same, taken on line 6—6 in Fig. 1.

Similar characters of reference are employed in the above described views, to indicate corresponding parts.

In an illustrative embodiment of this invention as shown, the humidifying device comprises a flat, relatively thin, rigid hollow body A closed at its forward end and open at its rearward end, and having suitable openings in its underside or bottom wall, through which moisture, emanating from a contained moisture charged absorbent body, can be emitted. The body A, thus generally characterized, can be made of any suitable moisture impervious material, but is desirably molded from a plastic material or fabricated from sheet plastic material.

The body of the humidifying device is formed by a top wall 10, a bottom wall 11, side walls 12 and a forward end wall 13 which are unitary one with another. The spacing of the top wall 10 relative to the bottom wall 11 is limited to provide the body with an internal chamber 14 which is open at its rearward end, and which is of sufficient height to accommodate a desired thickness of moisture absorbent pad 15. This pad 15 may be made of any suitable absorbent material, such as blotting paper or the like. The top wall 10 is imperforate, but the bottom wall is perforate. The form and arrangement of perforations or openings with which the bottom wall 11 is provided is subject to wide variation, but a satisfactory form and arrangement thereof, as shown, comprises a plurality of laterally spaced apart, longitudinally extending slots 16. The exterior surface of the forward end wall 13 is downwardly and outwardly inclined from the exterior surface of the top wall 10 to the exterior surface of the bottom wall 11, and is also of transversely curved conformation from side to side of the body, thus providing the forward end of the body 45 with a rounded external chamfered nosing 17. Affixed by its offsetting butt end 18 to the external surface of the top wall 10, at a point adjacent to the rearward open end of the body A, is a forwardly and longitudinally extending re-

50 silent clip arm 19, the free end portion 20 of which is yieldably biased toward and in engagement with the external surface of the body top wall. The body A is made of a width somewhat less than the distance between the face walls of 55 a cigarette package with which it is to be used,

and of a length substantially less than the distance between the side walls of said package.

Preparatory to use of the humidifying device, the pad 15 is removed and charged with moisture and then returned into the chamber 14 of the body A for enclosure within the latter.

In the use of the humidifying device, after a portion of an end wall of a cigarette package 21 has been torn away to provide an opening 22 in the end of the package, adjacent to one side thereof, through which cigarettes contained therein can be withdrawn for use, the body A is inserted bottom face downward, through the opening 22, to pass beneath the remaining portion 24 of said end wall, whereby to lie between the latter and the ends of the cigarettes 23. Such inserting movement of the body A into the package interior is facilitated by the chamfered nosing 11, the included and rounded contours of which will distend the package wall, so that the latter will readily yield to the ingoing movement of the body A without risk of being torn or otherwise mutilated. As the body A is thus inserted, the resilient clip arm 19 will pass over the external face of the said package end wall portion 24, so that said wall portion will be gripped between said arm and the top face of the body A, and consequently the humidifying device will be securely held against accidental displacement from its operative assembled inserted relation to the package. Since the body A is of substantially less length than the distance between the side walls of the package, when said body A occupies its operative inserted position within the package, it will clear the opening 22 formed in the package end wall, and consequently will not impede access to the cigarettes through said opening, or withdrawal of the cigarettes therethrough. Since the bottom wall 11 of the inserted body A faces the ends of the cigarettes contained in the package, moisture emanating from the moist pad 15 within the body will be emitted through the slot 16 of the bottom wall so as to contact the tobacco in the cigarettes, whereby to keep said tobacco in desirably moist condition, and thereby from quickly drying out.

After a package served by the humidifying device is empty, said device may be easily removed, again charged with moisture, if necessary, and then applied to another package. From this it will be understood that the device is substantially indestructible, and is well adapted for repeated use over and over again.

Having now described my invention, I claim:

1. A humidifier device for detachable insertion within a cigarette package through a cigarette access opening formed by tearing away a portion of an end wall of the package adjacent to a side thereof, said humidifier comprising a substantially rigid and flat rectangular hollow body closed at its forward end and open at its rear-

ward end, a moisture absorbent pad entered in said body through the rearward open end thereof, said body having a perforate bottom wall, and a longitudinally disposed, forwardly directed, resilient clip arm affixed by its rearward butt end portion to the top wall of said body, said body, in use, being inserted through said cigarette access opening of the package to lie between said package end wall in which said opening is formed and the ends of contained cigarettes opposed to said end wall, with the perforate bottom wall of the body opposed to said cigarette ends, and with the clip arm disposed exteriorly of said end wall to grip the same between said clip arm and the top wall of the inserted body, said body being of a length substantially less than the length of said package end wall whereby, when inserted within the package, it will leave a substantial portion of the cigarette access opening unobstructed.

2. The humidifier device of claim 1 wherein the perforate bottom wall of the body is formed by a plurality of laterally spaced apart longitudinal slots.

3. The humidifier device of claim 1 wherein the body is provided with a transversely rounded, downwardly and outwardly chamfered external nosing at its forward end.

4. A humidifier device for detachable insertion within a cigarette package through a cigarette access opening formed by tearing away a portion of a wall of the package, said humidifier device comprising a substantially rigid, flat hollow body, a moisture absorbent pad within the body interior, said body having a perforate bottom wall, said body being further provided with a transversely rounded, downwardly and outwardly chamfered external nosing at its forward end, and a resilient clip arm affixed to the top wall of said body, said body, in use, being inserted through said cigarette access opening of the package to lie between the package wall in which said opening is formed and the cigarettes contained in the package, with the perforate wall of the body facing said cigarettes and with the clip arm disposed exteriorly of said package wall to grip said wall between said clip arm and the inserted body, said body being of such length that, when inserted within the package, it will leave a substantial portion of the cigarette access opening unobstructed.
